UNITED STATES PATENT OFFICE.

LASSIE C. JOHNSON, OF ROANOKE, VIRGINIA.

LANTERN-LIGHTING DEVICE.

Application filed November 25, 1922. Serial No. 603,260.

To all whom it may concern:

Be it known that I, LASSIE C. JOHNSON, a citizen of the United States, residing at Roanoke, in the county of Roanoke and 5 State of Virginia, have invented certain new and useful Improvements in Lantern-Lighting Devices, of which the following is a specification.

The present invention relates to lamps, 10 lanterns and the like which use a fluid fuel and particularly to means for lighting the wick of such a lamp without removing the globe or chimney. The present invention is a continuation in part of my application, 15 Serial No. 448,752 filed March 1, 1921.

In lanterns of the usual type used by railroad men in flagging trains, there is a cup shaped container supported by a suitable frame and a burner carrying oil receptacle 20 removably fitting in the container. My present device for lighting a lantern consists of a tube which extends into said container and normally rests upon said receptacle, the inner end being projected to a point in 25 proximity to the wick of said burner and is provided with means for closing the end of the tube and for striking a match projected thereinto.

It is an object of my invention to so mount 30 the said tube on the container that it will not interfere with the removal of the oil receptacle from the container for any purpose as for filling or for cleaning the same.

Another object of the invention is to so 35 attach the tube to the container or other parts of the lantern, that the tube may be pivotally adjusted to bring the inner end into proper position relative to the wick to obtain the best results in lighting the said 40 wick.

In the drawings:

Figure 1 shows in elevation a fragmentary view of a lantern of the above mentioned type having my lighting tube attached thereto.

Figure 2 is a fragmentary view showing the container and the globe in vertical section and the relation of the tube to the container and to the removable oil receptacle.

Figure 3 is a fragmentary sectional view on an enlarged scale compared with Figures 1 and 2, showing the relation of the parts as in Figure 2.

Figure 4 is a detailed view showing the

nature of the hinged attachment of the tube to the container.

Referring to the drawings in detail:

10 designates the supporting and protecting frame of the lantern. 11 designates a 60 cup or container secured to said supports by the straps 12 which are secured to the container and embrace the supports. 13 designates an oil receptacle removably carried by said container and held in rigid relation thereto by means of spring clips 14. Secured on the upper end of the receptacle 13 is the usual burner 15, carrying the wick 16 and mounted on the container is the globe 17 which rests on the flange 18, which 70 projects inwardly from the walls of the container. The container is notched at 19 to receive the stem 20 of the wick operating mechanism, thereby definitely positioning the burner relative to the container, and the 75 container is preferably apertured as at 21 near its upper edge and in a position at approximately right angles to the plane of said wick. Extending inwardly from said aperture and having its inner end normally adjacent the burner of the lantern is a tube 22 closed at its inner end by means of a match striking device 23 which is provided with a long resilient arm 24 soldered or otherwise suitably attached to the side 85 of said tube. The inner end of the tube is preferably inclined and the match striking device is correspondingly inclined to rest snugly thereagainst, so as to prevent as far as possible air passing through the tube. 90

In order that the tube may not interfere with the removal of the lamp, for refilling the same or for cleaning or trimming the wick, and for purposes of adjustment of the inner end of the tube relative to the wick, 95 the tube 22 is mounted so that it may be flexed upwardly to a position as shown in dotted lines in Figure 2, in which position it is out of the path which the oil receptacle 13 must travel in being removed from the 100 container. The means by which the tube 22 is adapted to be flexed upwardly may be of any suitable character and as shown, comprises an arm 25 extending from the tube, the end of which is curved into an eye 26 105 through which is passed the pivot rod 27 soldered or otherwise secured to the container, the arm 25 being of sufficient length to permit the tube 22 to be turned upwardly to a vertical position within the container. 110

The flange 18 is notched at 18^a adjacent the tube 22 so as to receive the tube 22 and permit the same to assume the vertical position above referred to.

5 It will be noted from the above description that the tube 22 is so mounted that it may be turned to various positions of adjustment relative to the wick in lighting the lamp by the insertion of a match 28 into said tube 10 and striking the same by the roughened surface of the closing member 23 and that when it is desired to remove the receptacle 13 from the container, that the tube may be turned to a vertical position within the notch 18^a 15 and out of the path in which the oil receptacle must move in being lifted out of the receptacle. It will also be seen that I have provided a device by which a lantern or lamp to which the device is attached, may 20 be lighted in all conditions of weather regardless of rain or wind, with an assurance that the mechanism will unfailingly function, and which may be used where danger of conflagration is great as in barns, about 25 cotton gins or where flax or other readily inflammable material is stored. I have also provided a device which may be readily attached to lanterns or lamps of the character found commonly on the market with little 30 trouble and at a small cost.

Having described by invention, what I claim is:—

1. In combination with a lamp or lantern having a cup shaped container and a globe mounted on said container, a burner carrying oil receptacle removably carried by said container, said container having an aperture therein, a tube hinged adjacent said aperture and extending into said container above 35 said receptacle.

2. A lamp or lantern having a cup shaped member and a burner carrying fluid fuel receptacle therein, said cup shaped container being apertured adjacent its upper 45 end and a tube flexibly connected to said container for adjustment in a vertical plane and having its inner end normally resting adjacent the burner of said lamp.

3. In combination with a lamp or lantern having a cup shaped container provided 50 with a globe supporting flange adjacent its

upper end, a burner carrying receptacle removably positioned within said container, said container having an aperture adjacent its upper end and said flange having a notch 55 formed therein adjacent said aperture, a tube hinged to the outside of said container and projecting into said container, said tube normally resting upon the upper edge of said receptacle and held between the 60 same and the globe of said lamp or lantern and adjustable in a vertical plane to a position in which the tube rests in said notch and out of the line of travel of the receptacle when being removed from said container. 65

4. In combination with a lamp or lantern having a cup shaped container provided with a globe supporting flange adjacent its upper end, a burner carrying receptacle removably positioned within said container, said container having an aperture adjacent its upper end and said flange having a notch 70 formed therein adjacent said aperture, a tube within said container, a pivot rod secured to the outside of said container adjacent said aperture, said tube having an arm on its lower end projecting through said aperture, an eye on the end of said arm receiving said rod, said tube normally resting upon the upper edge of said receptacle and having its 75 inner end inclined, and an inclined spring supported closure resting against the inclined end of said tube for closing the same, said closure member having a roughened surface on its underside for striking a match 80 inserted into said tube.

5. In a device of the character described, a container having vertical side walls, a burner carrying fuel receptacle removably supported in said container, a lighting tube 90 extending into said container and adapted normally to rest above said receptacle, said tube being connected to said container so as to be movable out of the line of travel of said fuel receptacle when being removed from said container, and an aperture in said container in alignment with the bore of said tube when said tube is in normal position. 95

In testimony whereof I have hereunto set my hand.

LASSIE C. JOHNSON.
